DESIGN FOR A JEWELRY SETTING OR SIMILAR ARTICLE

Frederick J. Gaertner, Maplewood, N. J.

Application May 26, 1939, Serial No. 85,216

Term of patent 14 years

To all whom it may concern:

Be it known that I, Frederick J. Gaertner, a citizen of the United States, and a resident of Maplewood, in the county of Essex and State of New Jersey, have invented a new, original, and ornamental Design for a Jewelry Setting or Similar Article, of which the following is a specification, reference being had to the accompanying drawing, forming part thereof.

I claim:

The ornamental design for a jewelry setting or similar article, as shown.

FREDERICK J. GAERTNER.
